(57) **CLAIM**

The ornamental design of a spout assembly, as shown and described.

DESCRIPTION

FIG. 1 is a top, front, right side perspective view of a spout assembly and the like, showing my new design;
FIG. 2 is a top rear, left side perspective view thereof;
FIG. 3 is a front elevation view thereof;
FIG. 4 is a right side elevation view thereof;
FIG. 5 is a rear elevation view thereof;
FIG. 6 is a top plan view thereof; and,
FIG. 7 is a bottom plan view thereof.
The corresponding view for the left side elevation view is a minor image of FIG. 4.
